UNITED STATES PATENT OFFICE.

JAMES D. BENBOW AND WILLIAM L. BURNER, OF COLUMBUS, OHIO, ASSIGNORS TO THE KILBOURNE AND JACOBS MANUFACTURING COMPANY, OF COLUMBUS, OHIO, A CORPORATION OF OHIO.

THREE-WAY VALVE.

1,178,208.

Specification of Letters Patent.

Patented Apr. 4, 1916.

Application filed August 31, 1915. Serial No. 48,228.

To all whom it may concern:

Be it known that we, JAMES D. BENBOW and WILLIAM L. BURNER, citizens of the United States, residing at Columbus, in the 5 county of Franklin and State of Ohio, have invented certain new and useful Improvements in Three-Way Valves, of which the following is a specification.

Our invention relates to improvements in 10 three way valves, and includes especially the means for controlling the exhaust and outlet ports by the construction and operation of a rotary valve; in conjunction with a reciprocating valve adapted to be opened by the 15 rotary valve, for controlling the inlet port hereinafter described.

In the drawings which are hereto attached and hereby made a part of this specification, Figure 1 shows the valve casing in horizontal 20 section and the rotary valve disposed therein; Fig. 2 shows a transverse section through the valve and casing and the inlet valve; Fig. 3 shows the exhaust port closed as the valve is rotated to cause the inlet 25 port to open; Fig. 4 shows the intake position; Fig. 5 shows the exhaust position.

Referring to the drawings, 1 is a valve casing or casting in which is seated the rotary valve 2 held in proper engagement with 30 its seat by the cap 3 and the spring 4; the stem 5 permits the manipulation of the valve as desired. Valve 2 is cut away longitudinally to provide the segments 6 and 7 and the passageway 6^a and the free space 7^a 35 therein. The segments are rounded at one edge of each, 8 and 9, the rounded edge 8 providing for an earlier and more complete opening of the train pipe to exhaust, and a rolling or cam-like contact with the stem of 40 the intake valve when the latter is operated by said segment 6.

The inlet port 10 is controlled by the valve 11 which is seated through the influence of the spring 12 and is provided with 45 the stem 13 projecting into the valve chamber into the path of rotary valve 2. Communication between the valve chamber and the train line is provided through the port 14 and the exhaust takes place through the port 15. This valve construction may be inserted into a service line as desired and may 50 be employed with the motive fluid air or steam, as desired.

The operation and functions of the valve 55 construction are as follows:—The safety

position shown in Fig. 2 is attained by rotating valve 2 to close the port 14, and thereupon segment 6 is moved out of contact with valve stem 13, whereupon valve 11 is seated by the spring 12; by this movement segment 6 7 is brought into such position as to leave the exhaust port partially open, and any of the motive fluid which may leak in through the inlet valve 11 will constantly escape, whereby any harmful accumulation of the 6 motive fluid in the valve chamber is avoided, and the operation of the valve rendered entirely safe.

The closed position shown in Fig. 3 is attained by the rotation of the valve 2 to cause 7 segment 6 to open the inlet valve 11, or the valve 2 may be left in the position shown in said figure if desired. The position of parts therein shows that the exhaust port is entirely closed before the segment 6 is 7 brought into contact with the stem 13 of the valve 12 to open the latter and permit the air or steam to enter. As the valve is rotated the inlet port and the outlet port 14 are simultaneously opened and the segment 8 7 has meanwhile been maintaining the closure of the port 15, as shown in Fig. 4.

The exhaust position shown in Fig. 5 is attained by rotating the valve 2 to bring segment 6 out of contact with valve stem 13 8 and permit spring 12 to seat the valve 11, and to open the ports 14 and 15, whereupon the motive fluid confined in the train line is exhausted out through the port 15.

Valve constructions are known which will accomplish the simultaneous opening of inlet and outlet ports, and the opening of the exhaust port at the same time as the closing of the inlet port; but no three-way valve construction is known to us which is capable of assuring the escape through the exhaust port of any leakage coming through the inlet valve, or of providing for the positive closure of the exhaust port just prior to the opening of the inlet port; nor do we know any three-way valve construction which provides for rolling or cam-like contact between the rotary valve and the stem of the reciprocating valve, by which construction also the complete clearance of the outlet port is attained at an earlier point in the rotation of the rotary valve.

What we claim as new and desire to secure by Letters Patent is:—

1. In a chambered valve casing provided

with an inlet port, an outlet port, and an exhaust port, a spring actuated valve for closing said inlet port, a rotary valve cut away to provide two segments having a passageway therebetween through said valve, said rotary valve being adapted to be rotated to cause one of said segments to close said outlet port and to cause the other segment partially to close said exhaust port whereby any leakage through said closed inlet port may escape through said exhaust port.

2. In a chambered valve casing provided with an inlet port, an outlet port, and an exhaust port, a spring actuated valve for closing said inlet port, a rotary valve adapted to open said spring actuated valve cut away to provide two segments having a passageway therebetween through said valve, said rotary valve being adapted to be rotated to cause one of said segments to close said exhaust port and immediately thereafter to cause the other segment to open said spring actuated valve, whereby the positive closing

and maintaining the closure of the exhaust 25 port before and during the opening of the inlet port is effected.

3. In a three-way valve construction a rotary valve cut away longitudinally to form two segments thereon with a passageway 30 therebetween through said valve, a reciprocating valve structure adapted to control the inlet port, one of said segments having one of its edges round for the double purpose of permitting a rolling or cam-like contact thereof with said reciprocating valve structure to open the latter, and of furnishing earlier complete opening of the outlet port when the exhaust takes place. 35

In witness whereof we have hereunto subscribed our names at Columbus, Ohio, on this 23d day of August, 1915, in the presence of two witnesses.

JAMES D. BENBOW.

WILLIAM L. BURNER.
